CLAIM

The ornamental design for the microscope, as shown and described above.

DESCRIPTION

FIG. 1 is a top front right perspective view of an embodiment of a microscope showing our new design;
 FIG. 2 is a top front left perspective view thereof;
 FIG. 3 is a top rear right perspective view thereof;
 FIG. 4 is a bottom front right perspective view thereof;
 FIG. 5 is a bottom front left perspective view thereof;
 FIG. 6 is a bottom rear right perspective view thereof;
 FIG. 7 is a front view thereof;
 FIG. 8 is a rear view thereof;
 FIG. 9 is a top view thereof;
 FIG. 10 is a bottom view thereof;
 FIG. 11 is a left side view thereof; and,
 FIG. 12 is a right side view thereof.

The broken lines depict environmental subject matter only and form no part of the claimed design.
